H. C. PRIEBE

RAILROAD CAR TRUCK

Filed Feb. 12, 1924

Fig. 1.

UNITED STATES PATENT OFFICE.

HERMAN C. PRIEBE, OF BLUE ISLAND, ILLINOIS.

RAILROAD-CAR TRUCK.

Application filed February 12, 1924. Serial No. 692,372.

To all whom it may concern:

Be it known that I, HERMAN C. PRIEBE, a citizen of the United States, residing at Blue Island, in the county of Cook and the State of Illinois, have invented a certain new and useful Improvement in Railroad-Car Trucks, of which the following is a full, clear, concise, and exact description.

My invention relates to trucks for railroad cars and includes three point supports for the truck bolsters and the employment of **U** bolts as component members of the truck side frames. These **U** bolts are desirably also arranged to assemble the journal boxes with the side frames.

The invention, in all of its characteristics, will be explained in connection with the accompanying drawings in which Fig. 1 is a side view of a car truck made in accordance with the preferred embodiment of the invention; Fig. 2 is a view taken from beneath the truck as shown in Fig. 1, parts being shown in section and parts being removed; and Fig. 3 is a perspective view of a block which enters into the construction shown in Figs. 1 and 2.

Like parts are indicated by similar characters of reference throughout the different figures.

The truck side frame illustrated includes an upper arch bar 1, a lower arch bar 2, and the bolster guide bars 3 and 4 which depend from the upper arch bar and do not extend across the space between the arch bars in the structure shown. Each side of the truck has such a side frame. As the drawing only illustrates the construction at one side of the truck, the construction of but one side will be alone described, it being understood that such description pertains to the construction at each side.

Upright truck bolster supporting springs 5, 6 and 7 are located along each side frame between the arch bars and in the general plane thereof. In the construction of Fig. 1 these springs are seated directly upon the lower arch bar. The upright **U** bolt 8, which is not a novel part of the present invention, forming the subject matter of another application, Serial No. 692,369, filed Feb. 12, 1924, serves to define the positions of springs 5 and 7 and has its base below the lower arch bar and its sides passing through both of the arch bars with which the bolt is held in assembly by means of its nuts 9 threaded upon the upper ends of the

bolt sides. The bolster guide bars 3, 4 are formed with vertical bores which are coaxial with the bores of the upright springs 5, 7. The sides of the **U** bolt 8 are passed through aligned bores of the guide bars and said springs, this **U** bolt being in the general plane of the truck side frame. The truck bolster 10 extends between the sides of the **U** bolt 8 and is supported by the springs 5, 6 and 7 and has wings 11 at its bottom through which the sides of the bolt pass, these wings being interposed between the bolster guide bars and springs 5 and 7 underlying these guide bars. The intermediate upright truck bolster supporting spring 6 and its associate springs 5, 7 are so related that their axes and the axes of the sides of the **U** bolt 8 are in a common vertical plane that also includes the corresponding side frame. The bolster is guided in its movements by the side portions thereof, which are above the bolster wings 11, and the contiguous bolster guide portions. The sides of the **U** bolt 8 and the wings 11 of the bolster also take part in guiding the bolster. The brake hangers 12, 13 are carried by the supports 14, 15 integrally cast with the guide bars 3 and 4. These supports form the subject of another application, Serial No. 692,371, filed Feb. 12, 1924. The brake members 16 and 17 are carried at the lower ends of the brake hangers to be in normal relation with the wheels 18, 19 that are disposed at the ends of the contiguous side frame and whose axles 20 engage the bearings 21 which are housed within the journal boxes 22 suitably assembled with the side frame.

When construction of Figs. 1 and 2 is employed, a block 23 is interposed between the base of **U** bolt 8 and the bottom arch bar, there being a groove 24 in the bottom of this block and extending longitudinally of the side frame, and receiving the base of the **U** bolt 8.

The means shown for assembling the journal boxes with the contiguous side frame includes two frame members in the form of other **U** bolts, whose bases 26 are received in the grooves 27 that extend transversely through the block 23 and intersect the longitudinal groove 24 in this block. The grooves 27 are just sufficiently deeper than the groove 24 to enable the **U** bolt bases 26 to be held tightly by the base of the **U** bolt 8 between this **U** bolt base and the block 23. The symmetrically related

pairs of the **U** bolt sides 28, 29 continue from their **U** bolt bases longitudinally of the contiguous side frame of the truck and beneath the same, and beneath the journal boxes 22. One of the sides 28 of each of these underlying **U** bolts is bent near its end at an angle and passes upwardly through the ears 30 upon the side of the adjacent journal box 22 which is nearer the truck bolster and also through the approached ends of the two arch bars that overlie the journal box. The complementary **U** bolt side 29 of each underlying **U** bolt is continued below its associate journal box to the opposite side thereof and is bent to pass upwardly through the ears 31 upon this side of such journal box and thence through the approached ends of the arch bars. The bolt nuts 32 are screwed upon the upper ends of the upright portions of the **U** bolt sides 28, 29 to clamp the arch bars together and also to clamp the journal boxes between the arch bars and the contiguous **U** bolt sides 28, 29 that thus are in supporting relation to the journal boxes. The symmetrically related underlying **U** bolts whose sides 28, 29 thus take part in assembling the ends of the two arch bars and the journal boxes are so shaped and disposed as also to constitute lower members of the corresponding side frame. The upwardly bent end portions of these underlying **U** bolts are spaced apart, longitudinally of the contiguous side frame, as has been said in other words, to define with the ends of the arch bars and the horizontal portions of these **U** bolt sides, spaces to receive the journal boxes.

It is obvious that changes may be made without departing from the spirit of my invention.

Having thus described my invention I claim as new and desire to secure by Letters Patent the following:—

1. A side frame for car trucks including a frame member in the form of a **U** bolt whose sides are disposed and shaped to form two lower longitudinal and two end portions of the frame.

2. A side frame for car trucks including a frame member in the form of a **U** bolt whose sides are disposed and shaped to form two lower longitudinal and two end portions of the frame, said end portions being spaced apart longitudinally of the frame to receive a journal box therebetween.

3. A side frame for car trucks including upper and lower arch bars; and a **U** bolt whose sides maintain adjacent ends of said arch bars in assembly and are shaped and disposed also to constitute underlying portions of the frame.

4. A side frame for car trucks including upper and lower arch bars; and a **U** bolt whose sides maintain adjacent ends of said

arch bars in assembly and are shaped and disposed to afford space for receiving a journal box therebetween and to constitute underlying portions of the frame.

5. A side frame for car trucks including a **U** bolt whose sides are shaped and disposed to constitute two longitudinal portions of the frame.

6. A side frame for car trucks including a **U** bolt whose sides are shaped and disposed to constitute two underlying longitudinal portions of the frame.

7. A side frame for car trucks including upper and lower arch bars; and a **U** bolt having its sides bent and disposed to have their end portions upright and in holding relation to ends of the arch bars and portions contiguous to said end portions underlying the arch bars.

8. A side frame for car trucks including upper and lower arch bars; and a **U** bolt having its sides bent and disposed to have their end portions upright and in holding relation to ends of the arch bars and portions contiguous to said end portions underlying the arch bars, said end portions of the **U** bolt sides being spaced apart longitudinally of the frame to receive a journal box therebetween.

9. A side frame for car trucks including a **U** bolt having its sides bent and disposed to have their end portions upright and in holding relation to a complementary upper portion of the frame and portions contiguous to said end portions and at the bottom of the frame.

10. A side frame for car trucks including a **U** bolt having its sides bent and disposed to have their end portions upright and in holding relation to a complementary upper portion of the frame and portions contiguous to said end portions and at the bottom of the frame, said end portions of the **U** bolt sides being spaced apart longitudinally of the frame to receive a journal box therebetween.

11. A side frame for car trucks including upper and lower arch bars; and a **U** bolt having its sides bent and disposed to have their end portions upright and in holding relation to ends of the arch bars and portions contiguous to said end portions underlying the arch bars, the base of the **U** bolt being at a mid portion of the bottom of the frame and there assembled with the frame.

12. A side frame for car trucks including upper and lower arch bars; and a **U** bolt having its sides bent and disposed to have their end portions upright and in holding relation to ends of the arch bars and portions contiguous to said end portions underlying the arch bars, said end portions of the **U** bolt sides being spaced apart longitudinally of the frame to receive a journal box therebetween, the base of the **U** bolt being at

a mid portion of the bottom of the frame and there assembled with the frame.

13. A side frame for car trucks including a **U** bolt having its sides bent and disposed to have their end portions upright and in holding relation to a complementary upper portion of the frame and portions contiguous to said end portions and at the bottom of the frame, the base of the **U** bolt being at a mid portion of the bottom of the frame and there assembled with the frame.

14. A side frame for car trucks including a **U** bolt having its sides bent and disposed to have their end portions upright and in holding relation to a complementary upper portion of the frame and portions contiguous to said end portions and at the bottom of the frame, said end portions of the **U** bolt sides being spaced apart longitudinally of the frame to receive a journal box therebetween, the base of the **U** bolt being at a mid portion of the bottom of the frame and there assembled with the frame.

15. A side frame for car trucks including upper and lower arch bars; and a **U** bolt having its sides bent and disposed to have their end portions upright and in holding relation to ends of the arch bars and portions contiguous to said end portions underlying the arch bars, the base of the **U** bolt being at a mid portion of the bottom of the frame and there assembled with the frame, in combination with a second **U** bolt whose base is assembled with a mid and lower portion of the side frame and whose sides project upwardly, at their ends, the base of the first **U** bolt being interposed between the side frame and the base of the second **U** bolt to be thereby held in position.

16. A side frame for car trucks including upper and lower arch bars; and a **U** bolt having its sides bent and disposed to have their end portions upright and in holding relation to ends of the arch bars and portions contiguous to said end portions underlying the arch bars, said end portions of the **U** bolt sides being spaced apart longitudinally of the frame to receive a journal box

therebetween, the base of the **U** bolt being at a mid portion of the bottom of the frame and there assembled with the frame, in combination with a second **U** bolt whose base is assembled with a mid and lower portion of the side frame and whose sides project upwardly, at their ends, the base of the first **U** bolt being interposed between the side frame and the base of the second **U** bolt to be thereby held in position.

17. A side frame for car trucks including a **U** bolt having its sides bent and disposed to have their end portions upright and in holding relation to a complementary upper portion of the frame and portions contiguous to said end portions and at the bottom of the frame, the base of the **U** bolt being at a mid portion of the bottom of the frame and there assembled with the frame, in combination with a second **U** bolt whose base is assembled with a mid and lower portion of the side frame and whose sides project upwardly, at their ends, the base of the first **U** bolt being interposed between the side frame and the base of the second **U** bolt to be thereby held in position.

18. A side frame for car trucks including a **U** bolt having its sides bent and disposed to have their end portions upright and in holding relation to a complementary upper portion of the frame and portions contiguous to said end portions and at the bottom of the frame, said end portions of the **U** bolt sides being spaced apart longitudinally of the frame to receive a journal box therebetween, the base of the **U** bolt being at a mid portion of the bottom of the frame and there assembled with the frame, in combination with a second **U** bolt whose base is assembled with a mid and lower portion of the side frame and whose sides project upwardly, at their ends, the base of the first **U** bolt being interposed between the side frame and the base of the second **U** bolt to be thereby held in position.

In witness whereof, I hereunto subscribe my name,

HERMAN C. PRIEBE.
